CLAIM

We claim the ornamental design for a survival stove head multi-tool, as shown and described.

DESCRIPTION

FIG. 1 is a perspective view of a survival stove head multi-tool showing my new design;
 FIG. 2 is a right-side elevation view thereof;
 FIG. 3 is a left-side elevation view thereof;
 FIG. 4 is a front elevation view thereof;
 FIG. 5 is a back elevation thereof;
 FIG. 6 is a top plan view thereof;
 FIG. 7 is a bottom plan view thereof;
 FIG. 8 is a perspective view thereof, showing the survival stove head multi-tool collapsed; and,
 FIG. 9 is a perspective view showing the survival stove head multi-tool on the top, open-side of a circular container. The broken lines in FIG. 9 showing the circular container is included for the purpose of illustrating environmental structure and forms no part of the claimed design.
